US00D562162S

(12) **United States Design Patent** (10) **Patent No.:** **US D562,162 S**
Forlenza et al. (45) **Date of Patent:** **** Feb. 19, 2008**

(54) **TEMPERATURE INDICATOR**

(75) Inventors: **Albert Michael Forlenza**, Carrollton, TX (US); **Samuel Edward Ivey**, Richardson, TX (US); **Jerome F Krentel**, Covington, LA (US); **John Eglin Williams**, Covington, LA (US); **Joanne B. Haas**, Covington, LA (US); **Paula A. Schweikert**, Abita Springs, LA (US); **Kishore K. Kondabatni**, Atlanta, GA (US); **Richard E. Bailey**, Mandeville, LA (US)

(73) Assignee: **Cimex Medical Innovations, L.C.**, Covington, LA (US)

(**) Term: **14 Years**

(21) Appl. No.: **29/262,854**

(22) Filed: **Jul. 11, 2006**

(51) LOC (8) Cl. **10-04**

(52) U.S. Cl. **D10/53**

(58) Field of Classification Search D10/51-56;
62/3.2, 3.7, 6, 293

See application file for complete search history.

(57) **CLAIM**

The ornamental design for a temperature indicator, as shown and described.

DESCRIPTION

FIG. 1 is an isometric view of the design of the present invention;

FIG. 2 is top view of the design of the present invention;

FIG. 3 is a front view of the design of the present invention;

FIG. 4 is a side view of the design of the present invention;

FIG. 5 is a rear view of the design of the present invention; and,

FIG. 6 is a bottom view of the design of the present invention.

The broken line showing of line structure is included for the purpose of illustrating non-claimed subject matter and forms no part of the claimed design.
